UNITED STATES PATENT OFFICE.

DANIEL D. FRASER, OF BOSTON, MASSACHUSETTS.

WHIP-SOCKET ATTACHMENT.

SPECIFICATION forming part of Letters Patent No. 423,679, dated March 18, 1890.

Application filed August 5, 1889. Serial No. 319,721. (No model.)

To all whom it may concern:

Be it known that I, DANIEL D. FRASER, a citizen of the United States, residing at Boston, in the county of Suffolk, State of Massachusetts, have invented certain new and useful Improvements in Whip-Socket Attachments, of which the following is a specification, reference being had therein to the accompanying drawings.

10 This invention relates to certain new and useful improvements in attaching devices for whip-sOCKETS, and is designed more particularly as an improvement on the device for which I obtained Letters Patent, No. 403,260, dated May 14, 1889; and it has for its object to provide a stronger and better attachment than employed in my former device, dispensing with the perforation of the encircling band, which I have found from practice to very 20 materially weaken it and lessen its life.

The novelty in the present instance resides in the peculiarities of construction of the clamping-bracket and the novel construction, arrangement, and adaptation of parts whereby I lessen the number of parts, decrease the cost, and provide a more efficient and durable attaching means, all as more fully hereinafter described, shown in the drawings, and then particularly pointed out in the appended 30 claims.

The accompanying drawings clearly illustrate my present invention, in which drawings like letters refer to like parts throughout the different views, and in which—

35 Figure 1 is a side elevation, partly in vertical section, of a whip-socket provided with my improvement. Fig. 2 is a cross-section on the line $\alpha\alpha$ of Fig. 1. Fig. 3 is a perspective view of the clamping-bracket detached.

40 Referring now to the details of construction, A designates a whip-socket of any approved form and material.

B is my improved clamp-bracket formed with parallel bars B', having concaved under 45 faces B², conforming to the shape of the socket so as to fit closely thereagainst. At one end this bracket is formed with a right-angled portion B³, from which projects inward into the loop of the bracket a stud or pin B⁴. A lateral portion B⁵ is provided with an aperture B⁶, to receive the binding and clamping screw

D, hereinafter described. The opposite end of this bracket is formed with a loop B⁷, which extends slightly beyond the outer wall of the under cross-bar B⁸ and has its rear face substantially in vertical line with the outer face of said cross-bar, the outer face of the cross-bar being slightly inclined, as shown at B⁹ in Fig. 2.

C is the encircling band or ring which is 60 passed around the whip-socket A and at one end is formed with an aperture C', which is fitted over the stud B⁴ of the bracket, as shown in Fig. 2. After passing around the socket the other end of the band is passed through 65 the loop B⁷ up against the outer face of the cross-bar B⁸, thence across the bracket and parallel with the lateral portion B⁵ thereof. The set or clamping screw D is then passed through an opening in this end of the band or 70 ring and engages the screw-threaded opening B⁶ in the lateral portion B⁵ of the bracket, thus holding the parts firmly in position. This construction, it will be observed, avoids the use of the transverse screw D in my former device, 75 which, passing twice through the band or ring and through an opening in the bracket, I have found greatly weakened the parts and lessened its durability.

Besides forming a more durable connection, 80 the stud or pin on the bracket forms a better and more secure means of attachment than the screw of the old device.

Instead of forming the stud as shown in Fig. 3, I may sometimes prefer to make it in 85 the form as indicated by dotted lines in Fig. 2; but both forms serve sufficiently to hold the end of the band.

In order to avoid cutting away of the band or encircling ring where it passes through the loop B⁷, I form said loop slightly extended at the ends, as indicated by dotted lines in Fig. 3, so that the interior space of the loop will be at least equal to that of the outer dimensions of the clamping-bracket, so that the encircling band may be readily passed through 95 between the loop B⁷ and the cross-bar B⁸ without decreasing the width of the band.

What I claim as new is—

1. In a whip-socket-attaching device, the 100 combination, with a bracket formed with a stud extending lengthwise of the bracket, of

an encircling band or ring having one end secured to the said stud and the other end held to the bracket by means extending at right angles to the stud, substantially as set forth.

5. 2. In a whip-socket-attaching device, a bracket formed with substantially parallel sides, with a cross-bar at one end and a loop at said bar end, and at the opposite end with a vertical portion having formed integral therewith a stud extending parallel with the sides, substantially as set forth.

3. The combination, with a clamp-bracket formed with stud B⁴, cross-bar B⁸, and loop B⁷, of the encircling band or ring having one end secured on the stud and the other end passed through between the loop and the cross-bar and secured to the bracket by a screw extending at right angles to the stud independent of the first-mentioned end, substantially as set forth.

4. In a whip-socket-attaching device, a bracket formed with stud B⁴, lateral portion B⁵, having opening B⁶, and at the opposite end the cross-bar B⁸ and loop B⁷, the encircling band having one end held by said stud and the other end, after passing through between said loop and cross-bar, extending across the bracket lengthwise thereof, and a screw passed through an opening in the end of the band and engaging the opening in the lateral portion of the bracket independent of the first-mentioned end, substantially as shown and described. 25 30

In testimony whereof I affix my signature in presence of two witnesses.

DANIEL D. FRASER.
